COMBINED WATER CLOSET AND FLUSH TANK

Delferd Ferdinand Vietzke, El Reno, Okla.

Application June 6, 1955, Serial No. 36,392

Term of patent 14 years

(Cl. D4—5)

Fig 1

Fig 2

Fig 3

Fig 4

Fig. 1 is a front elevational view of a combined water closet and flush tank, showing my new design;

Fig. 2 is a side elevational view thereof;

Fig. 3 is a top plan view thereof; and

Fig. 4 is a perspective view thereof.

I claim:

The ornamental design for a combined water closet and flush tank, as shown.
